DESCRIPTION

1. Fluid distribution equipment

FIG. 1.1 is a top, front, left side perspective view of a fluid distribution equipment showing my new design;

FIG. 1.2 is a top view thereof;

FIG. 1.3 is a top, rear, left side perspective view thereof;

FIG. 1.4 is a left side view thereof; and

FIG. 1.5 is a rear view thereof.

Portions of the fluid distribution equipment shown in broken line are for the purpose of illustrating environmental structure and form no part of the claimed design.
